LOOP MODIFYING MECHANISM OF
STRAIGHT KNITTING MACHINES

Joseph Held, West Reading, Pa., assignor to Textile Machine Works, Wyomissing, Pa., a corporation of Pennsylvania

Application February 8, 1938, Serial No. 189,310

21 Claims. (Cl. 66—89)

The present invention relates to a full fashioned knitting machine adapted to make both the leg and foot portions of stockings.

Combined legger and footer full fashioned knitting machines have been proposed, but various reasons have coacted to prevent their use to any important extent, it having been the custom in the trade to have both leggers and footers in each factory. The design and proportions of such leggers and footers have become standardized and the parts compressed into as small a space as practical. The manufacture of the parts and their assembly have become routine matters, so that non-standard machines are more expensive. As the legger machine makes the widest portion of the stocking and the portion of the stocking knitted first, standard leggers are longer per section than standard footers, so that any attempt to convert one of these standard machines to a dual purpose machine necessarily must start with a legger machine. Although there are commercial considerations impelling knitters to perform both legging and footing operations on one machine there has never been a practical conversion of the standard legger to a dual purpose machine.

It is an object of the present invention to provide an arrangement whereby an existing standard full fashioned legger knitting machine may be converted to perform footer operations as well as legger operations under commercial conditions and with only minor changes in the mechanism.

Combined leggers and footers have been built as such, but have suffered from the fact that such dual purpose machines have been uneconomical of space, requiring more room per knitting section in order to prevent mechanical interference between the parts.

Another object of the present invention is to provide an arrangement for dual purpose knitting machines which shall have a relatively high space efficiency.

Prior dual purpose full fashioned knitting machines, moreover, have been longer per knitting section than standard legger machines.

Another object of the invention is to provide a full fashioned knitting machine having one or more knitting sections of the usual length for standard legger machines and adapted to perform all the usual operations of both leggers and footers.

One of the especially serious difficulties faced by designers of dual purpose full fashioned knitting machines has been that of preventing interference between the full length picot or

lock stitch bars of the legger type machine and the narrowing combs.

Another object of the invention is to provide an arrangement for full fashioned knitting machines permitting the use of picot bars of the legger machine type and narrowing combs of the footer machine type in knitting sections of the width ordinarily used in leggers, but without mechanical interference.

With these and other objects in view, which will become apparent from the following detailed description of the illustrative embodiment of the invention shown in the accompanying drawings, my invention resides in the novel elements, features of construction and arrangement of parts in cooperative relationship as hereinafter more particularly pointed out in the claims.

In the drawings:

Figure 1 is a front elevational view of a portion 20 of a common type of knitting machine having my invention applied thereto;

Fig. 2 is a transverse sectional view taken on the line 2—2 of Fig. 1;

Fig. 3 is a view similar to Fig. 2 but showing 25 certain of the parts in different relative positions;

Fig. 4 is a fragmentary plan view of some of the parts appearing in Figs. 2 and 3 taken substantially on the line 4—4 of Fig. 2;

Fig. 5 is a transverse sectional view taken on line 5—5 of Fig. 1;

Fig. 6 is a fragmentary view similar to Fig. 5 but showing the parts in different relative positions;

Fig. 7 is a fragmentary sectional view of a portion of Fig. 6, taken substantially on the line 7—7 of Fig. 8;

Fig. 8 is a front elevational view on an enlarged scale of the parts shown on the upper 40 right portion of Fig. 1, certain parts however being shown in different relative positions;

Fig. 9 is a fragmentary front elevational view, partly in section, showing certain of the parts appearing in the right hand portion of Figs. 2 and 3, parts being omitted for purposes of illustration;

Fig. 10 is a fragmentary sectional view taken substantially on the line 10—10 of Fig. 9;

Fig. 11 is a fragmentary sectional view on an enlarged scale taken substantially on the same line of section as Fig. 6 and illustrating certain of the parts thereof;

Fig. 12 is a vertical sectional view taken substantially on the line 12—12 of Fig. 11;

Fig. 13 is a sectional plan view taken substan-

tially on the line 13—13 of Fig. 2, certain parts being broken away to show elements behind the line of section;

Fig. 14 is a view similar to Fig. 13 but showing the parts in different relative positions;

Fig. 15 is a vertical sectional view taken substantially on the line 15—15 of Fig. 2;

Fig. 16 is a vertical sectional view taken substantially on the line 16—16 of Fig. 3; and

Fig. 17 is a vertical sectional view taken substantially on the line 17—17 of Fig. 13.

In the drawings and description, only those parts necessary to a complete understanding of the invention have been set forth; further information as to the construction and operation of other elements not herein specifically pointed out, but which are usual and well known, being available in the pamphlet entitled "Full Fashioned Knitting Machines," copyright 1920, and in the "Reading" Full Fashioned Knitting Machine Catalogues, copyright 1929 and 1935, published by the Textile Machine Works, Reading, Pa., and in a pamphlet entitled "Knitting Machine Lectures," published in 1935 by the Wyomissing Polytechnic Institute, Wyomissing, Pennsylvania.

The machine shown in the drawings comprises a framework 19 on which is mounted a series of machine sections 21, each intermediate two transverse frames 20 and including two needle banks 22 which receive knitting motions from cams on a main cam shaft 23 through suitable connections or mechanism in the usual manner. For purposes of narrowing the fabric when desired, each needle bank has associated therewith a pair of wide combs 25—25 and a pair of narrow combs 26—26. For purposes of making lock stitches for picot edges and other purposes, each needle bank has associated therewith a lock stitch or lace bar 27. Combs 25 and 26 and bars 27 all have points therein adapted when the combs or bars are dipped from a certain level to lift certain loops from the needles of banks 22 and, after the combs or bars have been lifted to clear the needles and shifted horizontally, to place the lifted loops on other needles of the banks. In order to carry out such transferring operations, combs 25 and 26 and bar 27 are connected in the usual way to a front narrowing shaft 28. Shaft 28 is mounted to swing up and down in the usual way, being fixed at the forward ends of arcuate links 31 (Fig. 2) mounted at their rear ends on a rear narrowing shaft 32 which is turnably mounted in bearings secured to the framework 19. By means of this arrangement, the narrowing shaft 28 follows an arcuate path, with shaft 32 as a center, during the up and down movement thereof.

The combs 25 and 26 are mounted directly on rods 33 which are slidable but not rotatable in brackets 34 fixed to front narrowing shaft 28. The horizontal motions of the rods 33 which occur in the narrowing operation are supplied by nuts 29—29, Fig. 1, on the narrowing heads 30 in the usual way. The lock stitch bars 27 are arranged in two groups each fixed to a shaft 35 by arms 36, shafts 35 being swivelled in blocks 37 fastened to the front faces of brackets 34 so that bars 27 may be swung down into the position shown in Figs. 6, 8 and 11 in which they may operate on the fabric or may be swung up into the rest or inoperative position shown in Figs. 1, 2 and 5. Only one shaft 35 is shown but the ordinary arrangement provides that the ends of two such shafts approach each other at the

center of the machine and means is provided to insert a wedge shaped block or cam (not shown) between the ends of the two shafts 35 to provide for the necessary horizontal motions of the shafts

5 when transferring stitches. Two other shafts 38 and 39 are shown mounted in blocks 31. Shafts 38 and 39 are for carrying covering knives and special lace points respectively (not shown) and are not concerned with the present invention.

10 The invention illustrated is embodied in a standard legger machine and thereby provides an arrangement for knitting both foot and leg portions of the flat blanks used in making full fashioned stockings. The machine shown therefore requires needle banks 22 of the length needed for legger machines and the narrowing comb arrangement needed for footer machines. However, if the ordinary arrangements of combs and lock stitch bars are used, interference occurs unless the sections are lengthened. The arrangement of the present invention permits the use of the footer type narrowing combs with picot or lock stitch bars and needle bars of the legger type in knitting sections and machines of the length per section usual in leggers. In accordance with the invention, this is accomplished by raising the combs 25 and 26 above the level from which they begin their narrowing operations and operating the picot bar or bars while the combs are so raised. The arrangement for this purpose includes arms 36 longer than the ordinary so that one or more lock stitch bars 27, may operate from a top position (usually a rest position), Fig. 3, of the front narrowing shaft 28 instead of from the lower position thereof shown in Fig. 2, it being common to provide means for raising and lowering the front narrowing shaft from a lower operating level to a higher one from which no operations are usually performed because the points would not touch the fabric if a dipping motion were initiated from the higher level. Ordinarily, the narrowing combs and picot bars both start their functional movements from the lower position of Fig. 2, the combs being spread apart when desired to permit the picot bars to be lowered without interference. As shown, the arms 36 for the lock stitch bars are longer than usual so that the lace points in a bar or bars 27 may operate on the fabric, if the front narrowing shaft 28 is dipped, when shaft 28 is initially at the higher level of Fig. 3. Means for elevating the front narrowing shaft 28 to the level of Fig. 3 at which level the narrowing points of the combs 25 and 26 are prevented from operating on the fabric even though the shaft 28 is dipped, are provided in ordinary legger and footer machines and comprise vertical links 42, one end of each of which provides a bearing for the shaft 28. Links 42 are pivoted at their lower ends to horizontal levers 43 at points near the rear and free ends thereof, the forward forked ends of levers 43 being pivoted to the frame on an axis 44. The rear ends of levers 43, however, project somewhat to the rear of their points of connection with links 42 and are notched at their extreme rear ends to receive the upper ends of thrust links 45 which are pivoted to the arm 40. A crank 46 is securely mounted on a shaft 47 and can be rocked along with shaft 47 by a handle 48 at the front of the machine which is connected to crank 46 by a link 49. When handle 48 is raised as shown in Fig. 3, the crank or lever 46 is drawn forwardly and levers 43 are thrown

upwardly to engage levers 43 and lift the shaft 28 and the connected parts. The combs 25 and 26 are thereby raised so far above the knitting needles in banks 22 that the narrowing points in the combs cannot touch the fabric to operate on it even when dipped by the ordinary dipping means. It will be understood that handle 48 must be in the down position of Fig. 2 when narrowing or other loop transferring operations are performed so that the cams 67 may be effective. 10

The position of the combs 25 as shown in Fig. 2 is approximately that from which the dipping motion which initiates a narrowing operation starts. However, the arms 36 are long enough to bring bars 27 and the points carried thereby downward from the rest position shown in Figs. 2 and 5 to that shown in Fig. 6 and in which the points in the lock stitch bar 27 are the same distance from the knitting needles when shaft 28 is raised as the points in combs 25 and 26 are when shaft 28 is down as in Figs. 1, 2 and 5. Therefore, when the bars 27 are in the position shown in Fig. 6, the points in bars 27 may be used to transfer certain stitches to make a lock stitch structure. When so lowered, arms 36 may be held to position bars 27 properly in the horizontal direction by screws 52 (Figs. 6, 8 and 11) which are fixed in arms 36 and rest against shaft 39.

However, due to the arcuate movement of front narrowing shaft 28 when raised and lowered, the points in combs 25 and 26 project forward enough as shown in Figs. 8, 11 and 12 to enter the volume outlined by bars 27. In order to prevent interference between the points and bars, bars 27 are shown cut away to form recesses 53, 53 at the corners of the bars and a central recess 54. As is clear from Figs. 8, 11 and 12, recesses 53 and 54 are deep enough to prevent interference of the points in combs 25 and 26 with the operation of the bars 27.

It will be understood that means are ordinarily provided for holding the bars 27 fixed in the correct angular position during the periods the bars 27 are to be dipped to pick up loops from the needles. A commonly used arrangement for this purpose is shown in Figs. 1, 7 and 8 and comprises thin flat extensions 55 projecting downwardly from the lower ends of certain of the blocks 37. Arms 56 fixed on the lock stitch shaft 35 are of a length proper to reach the level of extensions 55 when bars 27 have been swung down into their lower position and arms 56 have off-sets 57 at their free ends which extend rearwardly when the arms are lowered so that off-sets 57 are adapted to overlie extensions 55 when viewed as in Fig. 7. Also, off-sets 57 have grooves 58 therein adapted to receive extensions 55 to prevent shaft 35 and bars 27 from turning during dipping operations. Shaft 35 has pivoted thereon a camming piece 59 having a bevelled face 62 arranged for pivotal movement between a collar 61 fixed on shaft 35 and an abutment 63, shown in the form of a screw fixed in a bracket 64 on the front narrowing shaft 28. The camming piece 59 is biased toward abutment 63 by means of a spring 65 coiled on shaft 35, which moves shaft 35 in the direction to bring off-sets 57 in the same plane transverse to shaft 35 as extensions 55, see Fig. 8. In order to move bar 27 to its raised or inoperative position or to its lower position where the bar acts on the fabric, the camming piece 59 must be in the position of Fig. 1, so that off-sets 57 will clear the extensions 55 of

blocks 37. After bar 27 has been lowered to the position of Fig. 8, camming piece 59 is given a partial rotative movement, permitting the springs 65 to move the shaft 35 and the off-sets 57 to the position of Fig. 8 where the extensions 55 are embraced by the grooves 58, to hold the bars 27 against swinging movement without interfering with the shifting thereof lengthwise of the machine.

As the combs 25 are dipped to act on certain loops on the needles when shaft 28 is at one level and bars 27 are dipped to act on certain loops on the needles when shaft 28 is at another level, the dipping means must be capable of acting under both conditions. The arrangement shown for this purpose comprises a novel lever and cam follower arrangement as more clearly appears hereinbelow, and also the usual circular idling cams 66 and the dipping cams proper 67 arranged in pairs side by side on cam shaft 23. Nearly horizontal arms or levers 68 are pivoted on axes 44 to lie beneath levers 43 and extend between the forks at the forward ends thereof. Levers 68 have gudgeons 69 fixed therein in position to support rollers 70 for bearing on cams 66 and 67. When shaft 23 is in the knitting position, rollers 70 are in the planes of circular idling cams 66. When shaft 23 has been shifted to narrowing position by known or preferred means 71, rollers 70 are in the planes of cams 67. When therefore the operator prepares the machine for dipping shaft 28, he lowers handle 48 to the position shown in Figs. 2 and 4 while the shaft 23 is still in knitting position, thereby placing the weight of shaft 28 and attached parts on rollers 70 and thereby on idling cams 66 which maintain shaft 28 at its initial level. When now shaft 23 is shifted by means 71 at the time the high points of cams 67 have been aligned with rollers 70, the rollers are brought to bear on cams 67 which act to dip shaft 28 during their revolution. If shaft 28 is then in its lower initial position as shown in Fig. 2, combs 25 or 25 and 26 will act on the fabric when dipped. If, however, shaft 28 is in its upper initial position (Fig. 3) when the rollers 70 are supported on cams 67, and bars 27 have been lowered as in Figs. 6, 7, 8 and 11, the points in bars 27 will act on the fabric when dipped.

In order to maintain shaft 28 in its upper position prior to dipping after the weight of the shaft 28 has been placed on rollers 70 on the cams 66, the rear ends of levers 43 and 68 are spaced apart, as in Figs. 3 and 16. As is clear from Figs. 2 and 15 in one relative position of the parts, shoulders 72 on levers 43 bear directly on flats at the rear ends of levers 68. In order now that combs 25 and 26 may not act on the fabric when bars 27 are lowered and shaft 28 is dipped by cam 67, the rear ends of levers 68 are grooved transversely to receive slides 73 (Figs. 2 and 13 to 16) the upper surfaces of which are in general flush with the surface of the levers 68, but which carry upwardly projecting bosses 74a in which are bolts 74 which, when the slides 73 have been shifted from the position shown in Figs. 2 and 15 to that shown in Figs. 3 and 16, lie in the planes of levers 43 so that the levers 43 are spaced from levers 68, and shaft 28 and levers 68 are supported in their upper position when roller 70 is on cam 66. In order to effect this relative position of the parts, the operative throws handle 48 up until he lifts levers 43 high enough to slide bolts

74 beneath levers 43 while rollers 10 are on cams 66. Suitable means must be provided whereby the operative may shift slides 73 and that shown for this purpose comprises levers 51 pivoted (Fig. 17) on levers 68 and lying between levers 43 and 68. The rear ends of levers 51 are connected to slides 73, a bolt and slot connection (Figs. 14-16) being shown, while the forward ends of levers 51 (Figs. 3, 13 and 14) extend through the forks of levers 43 beyond the forward ends of levers 43 and 68 and bend downward and then rearward just above a rod 80. It will be understood that a lifting lever 45 and a spacing piece or slide 73 are provided per each lever 43 but that only one handle 48 is provided per machine.

The lower ends of levers 51 are widened to form arcuate rearwardly inclined surfaces 79-79 (Figs. 2, 13 and 14) adapted to roll between collars 81-81 on rod 80 so that a longitudinal movement of rod 80 swings levers 51 to move the slides 73. Rod 80 is mounted to slide parallel to cam shaft 23 and is supported on the front of the machine in brackets 82 so as to be operable by hand at the will of the operative. If now lock stitch bars 27 have been swung down from their upper rest position shown in Fig. 2 to that shown in Figs. 6, 7, 8 and 11 and the off-sets 57 engaged with extensions 55 to hold bars 27 in fixed angular position, the points in lock stitch bars 27 will be dipped to act on the fabric in the revolution following upon the next shift of cam shaft 23.

It is apparent that the bars 27 should not be lowered unless combs 25 and 26 have been raised by raising shaft 28. In order to prevent the operatives from lowering bars 27 while combs 25 and 26 are in their lower position, shafts 35 have sectors 75 (Fig. 5) fixed thereon which extend upwardly and somewhat rearwardly therefrom when bars 27 and arms 36 are in the upper or rest position. Shoes 76 are provided and arranged to engage sectors 75 to prevent bars 27 from being lowered except when desired. For this purpose, shoes 76 are fixed to the upper and rear ends of bent levers 77, one for each shaft 35 but only one of which is shown, which are pivoted near their centers at points 78 and are biased by springs 60 to hold shoes 76 to the rear. The forward and lower ends of levers 77 may be held up to throw shoes 76 rearwardly close to sectors 75 to prevent the sectors from turning forward and to thereby lock bars 27 against turning forwardly and downwardly. Means are provided to latch lever 77 and shoe 76 in locking position. The means shown for this purpose comprises a bolt 83 (Figs. 5 and 9) fixed in the lower forward end of each of levers 77 and adapted when the lever is raised to locking position to permit a latching collar 84 fixed on a rod 80 to move under bolt 83 to hold lever 77 and shoe 76 in the locking position shown in Fig. 5. When collar 84 is moved out from under bolt 83, the lever 77 is free to be moved by sector 75 against the action of springs 60 into the position shown in Figs. 6 and 9 in which arms 36 can be swung around to lower bars 27.

A handle 85 is fixed to rod 80 to facilitate movement of the rod by the operative against the action of a spring 86 (Fig. 9). Spring 86 is connected so it tends to move rod 80 toward the right when viewed as in Fig. 9 to bring collars 84 beneath bolts 83 and to throw levers 51 in the direction to remove bolts 74 from beneath levers 43. In order to maintain a stable condition when bars 27 are down as shown in Fig. 8 in preparation

for transferring stitches, a latch lever 87 is pivoted on a cap nut 88 mounted on the reduced threaded end of a bolt 50 which serves as the axis 44 for a pair of levers 43 and 68 and is held 5 in a transverse frame member 20. After the front narrowing shaft has been raised from the position of Fig. 2 to that of Fig. 3 by lifting of the handle 48, the handle 85 and consequently rod 80 is moved leftward from the position of Fig. 1 to the position shown in Fig. 9, thereby causing levers 51 to move slides 73 and bolts 74 from the positions of Fig. 15 to the right to the positions of Fig. 16, removing collars 84 from under bolts 83 and permitting transfer bars 27 10 to be swung into their operative positions shown in Figs. 6, 7, 8 and 11, as spring 90 (Fig. 10) acts to latch the parts in this position by throwing latch lever 87 forward and downward to bring a lug 91 thereon alongside a collar 92 on rod 80 to hold rod 80 to the left against the action of spring 86. As soon as the operative has finished using bars 27, he may lift them to the rest position of Fig. 5 and thereupon the springs 60 will swing levers 77 so that collars 84 can pass 15 under bolts 83. If then the operative raises handle 48 to sustain shaft 28 and the parts connected thereto, he may lift lever 87 and permit spring 86 to throw rod 80 to shift bolts 74 out from under levers 43 and, at the same time, throw collars 84 under bolts 83 to lock the bars 27 in their 20 rest positions. A collar 89 on shaft 80 limits the throw of shaft 80 under influence of spring 86 by contacting a bearing 82 for shaft 80 to thereby ensure that a collar 84 shall lie beneath a bolt 83 on a lever 77. The front narrowing shaft 28 and attached parts may then be lowered to bring the narrowing combs 25 and 26 into position from which they may, when dipped, operate on the loops. A safety release unit generally indicated at 41 and mounted on back beam 18, see Figs. 2, 3 and 4, is commonly employed, and cooperates with the crank 46 and the narrowing lift shaft 47, in well known manner, to prevent a sudden downward drop of the loop modifying mechanism comprising the narrowing combs, lock stitch bars and associated mechanism when the front narrowing shaft 28 is released from its top position. For further details concerning safety release mechanisms of the type indicated at 41, reference may be had to the U. S. Patent No. 1,928,283 which issued to John G. Ennis on September 26, 1933.

Of course, the improvements specifically shown and described by which I obtain the above results, can be changed and modified in various ways without departing from the invention herein disclosed and hereinafter claimed.

What I claim is:

1. In a full fashioned knitting machine, in combination, a cam shaft, a second shaft, a cam and lever means arranged to sustain said second shaft at constant level when the cam shaft is in knitting position and to dip said second shaft when the cam shaft has been shifted, and means whereby said cam and lever means may sustain said second shaft at two different levels and dip it from either of said levels as desired through operative cycles of corresponding magnitude.

2. In a knitting machine, a shaft mounted to move up and down, a series of needles, point means including a lock stitch bar and a narrowing comb supported by said shaft adapted to cooperate with said needles, and means for actuating said shaft from different levels to effect

corresponding movement cycles of each of said point means.

3. In a knitting machine, a single means mounted to move up and down, a series of needles, point means including a lock stitch bar and a narrowing comb supported by said single means adapted to cooperate with said needles, and means for actuating said single means from different levels to effect corresponding movement cycles of each of said point means.

4. In a knitting machine, in combination, a shaft arranged to operate from an upper and from a lower starting position to effect an upper and a lower operative cycle of corresponding magnitude, a first and a second loop manipulating means supported by said shaft, said first loop manipulating means being operated upon movement of said shaft through its upper cycle and said second loop manipulating means being operated upon movement of said shaft through its lower cycle.

5. In a full fashioned knitting machine, in combination, a cam shaft, a front narrowing shaft actuated by said cam shaft from upper and lower starting positions to effect upper and lower operative cycles respectively of corresponding magnitude, narrowing combs and a point bar supported by the front narrowing shaft, said narrowing combs adapted to act on the fabric when the front narrowing shaft is actuated through its lower cycle and the point bar adapted to act upon the fabric when the front narrowing shaft is actuated through its upper cycle, and linkage intermediate said shafts for selectively conditioning the front shaft to operate in the cycle desired.

6. In a full fashioned knitting machine, in combination, a cam shaft, a front narrowing shaft actuated by said cam shaft from upper and lower starting positions to effect upper and lower operative cycles respectively, narrowing combs and a point bar supported by the front narrowing shaft, said narrowing combs adapted to act on the fabric when the front narrowing shaft is actuated through its lower cycle and the point bar adapted to act upon the fabric when the front narrowing shaft is actuated through its upper cycle and rod operated means for preventing said front narrowing shaft from operating through its lower cycle while said point bars are operatively positioned.

7. In a full fashioned knitting machine, in combination, a cam shaft, a front narrowing shaft actuated by said cam shaft through upper and lower operative cycles, narrowing combs and a point bar supported by the front narrowing shaft, said narrowing combs adapted to act on the fabric when the front narrowing shaft is actuated through its lower cycle and the point bar adapted to act upon the fabric when the front narrowing shaft is actuated through its upper cycle and means for preventing said front narrowing shaft from operating through its lower cycle while said first point bars are operatively positioned.

8. A full fashioned knitting machine having a needle bank, a lock stitch bar having points and arranged to cooperate with the needles of said bank, combs having points for acting when desired on the selvages of fabric knitted by said bank, and cutout portions in said bar to receive points on said combs.

9. A full fashioned knitting machine having a cam shaft, a front narrowing shaft, combs and a lock stitch bar on said shaft, means whereby the combs may be raised above and to the rear of the level at which they operate on the fabric,

an arm pivotally carried by said front shaft to which said lock stitch bar is fixed, said pivoted arm having a length to bring the points on the lock stitch bar to the usual level of the narrowing points when said combs have been raised and the lock stitch bar has been swung down, a cam and lever means arranged to sustain said narrowing shaft at constant level when the cam shaft is in the knitting position and to dip said narrowing shaft when the cam shaft has been shifted, and means whereby said cam and lever means may sustain and dip said narrowing shaft either at and from the position in which the combs are raised or at and from the position in which the combs may operate.

10. In a full fashioned knitting machine, in combination, a cam shaft, a front narrowing shaft, combs and a lock stitch bar on said second shaft, a cam and lever means arranged to sustain said narrowing shaft at constant level when the cam shaft is in knitting position and to dip said narrowing shaft when the cam shaft has been shifted, and means whereby said cam and lever means may selectively sustain said narrowing shaft at two different levels in a given angular position of the cam shaft and dip it from either of said levels as desired through operative cycles of corresponding magnitude.

11. In a full fashioned knitting machine, in combination, a cam shaft, a front narrowing shaft, and a cam and lever means arranged to sustain said front shaft at constant level when the cam shaft is in knitting position and to dip said front shaft when the cam shaft has been shifted, said sustaining and dipping means comprising a member slidably transversely of the lever portion of said means for varying the height at which the shaft is held in a given angular position of the cam portion of said means.

12. In a full fashioned knitting machine, in combination, a cam shaft having sustaining and dipping cams thereon and arranged to be shifted, a front narrowing shaft, a lever pivoted at one end and connected to said narrowing shaft at the other, a second pivoted lever having a cam follower thereon arranged to rest on said sustaining cam when the cam shaft is in knitting position and on said dipping cam when the cam shaft has been shifted and having a contact area for supporting said first lever, and a member slidably between said levers to sustain said narrowing shaft at a higher or lower level as desired at any given angular position of said cams.

13. In a full fashioned knitting machine, the combination of a front narrowing shaft, combs and a lock stitch bar supported on said shaft each having operative and inoperative positions, a cam shaft arranged to be shifted and having sustaining and dipping cams thereon, a lever arrangement intermediate said narrowing shaft and said cams and including a cam follower arranged to contact said sustaining cam when the cam shaft is in one position and said dipping cam when the cam shaft has been shifted from said position, and means to prevent said lock stitch bar from being placed into operative position when said combs are in operative position.

14. In a full fashioned knitting machine, the combination as set forth in claim 13 together with means to hold said combs in inoperative position when said lock stitch bar is in operative position.

15. In a full fashioned knitting machine, in combination, a front narrowing shaft, combs and a lock stitch bar supported from said shaft,

a cam shaft shiftable from knitting to narrowing position and return, sustaining and dipping cams on said cam shaft, a lever means having a cam follower thereon for contacting said cams, means associated with said lever means to hold said narrowing shaft at a level when said follower is on the sustaining cam to render said combs inoperative, and means to hold said last mentioned means in operative position.

16. In a full fashioned knitting machine, the combination as set forth in claim 15 together with means to hold said lock stitch bar in inoperative position when said combs are in position to operate.

17. In a full fashioned knitting machine, the combination as set forth in claim 15 together with means tending to throw the holding means into inoperative position, a latch to lock said holding means in operative position, and means to hold the lock stitch bar in inoperative position when said latch is not in operation.

18. In a full fashioned knitting machine, the combination of a front narrowing shaft mounted to occupy upper and lower positions, combs and a lock stitch bar supported on said shaft, said combs arranged to be capable of operation when said shaft is in its lower position and said bar arranged to be capable of operation when said shaft is in its upper position, a cam shaft arranged to be shifted and having sustaining and dipping cams thereon, a lever arrangement intermediate said narrowing shaft and said cams and arranged to support the narrowing shaft, means to lock said lock stitch shaft in inoperative position when said narrowing shaft is in its lower position, and

means to hold said narrowing shaft in its upper position with respect to any given angular position of said cams to permit operation of said lock stitch bar.

19. In a full fashioned knitting machine, the combination as set forth in claim 18 together with means tending to throw said holding means out of action and a latch to hold it in action.

20. In a knitting machine, in combination, a shaft mounted to swing up and down about an external pivot, operator controlled means for setting said shaft at an upper and a lower position, automatic means for dipping said shaft from either of said positions, narrowing combs supported from said shaft, means for operating said combs to act on the fabric when said shaft is dipped from said lower position, and a lock stitch bar supported from said shaft, and means for operating said bar to act on the fabric when the shaft is dipped from the upper of said positions.

21. In a knitting machine, in combination, a shaft mounted to swing up and down about an external pivot, operator controlled means for setting said shaft at an upper and a lower position, automatic means for dipping said shaft from either of said positions, narrowing combs supported from said shaft, means for operating said combs to act on the fabric when said shaft is dipped from said lower position, and a lock stitch bar having recessed portions for receiving points on the combs, said bar being supported from said shaft, and means for operating said bar to act on the fabric when the shaft is dipped from the upper of said positions.

JOSEPH HELD.
